WINDROWER TRACTION UNIT HOOD AND BODY PANELLING

Joe Paul Leinhauser, Ottumwa, Iowa, and James Mervyn
Conner, Mamaroneck, N.Y., assignors to Deere & Com-
pany, Moline, Ill.

Filed Jun. 27, 1973, Ser. No. 374,027

Term of patent 14 years

Int. Cl. D15—03

U.S. Cl. D40—1 E

FIG. 1

FIG. 3

FIG. 1 is a left front perspective view of a windrower traction unit hood and body panelling, showing our new design;

FIG. 2 is a right side elevation thereof, the broken lines representing the traction unit shown for illustrative purposes only; and

FIG. 3 is a left rear perspective view thereof.

We claim:

The ornamental design for a windrower traction unit hood and body panelling, substantially as shown and described.
